UNITED STATES PATENT OFFICE.

GEORGE G. FLOYD, OF CHICAGO, ILLINOIS, ASSIGNOR TO AMERICAN STEEL FOUNDRIES, OF NEW YORK, N. Y., A CORPORATION OF NEW JERSEY.

COUPLING-POCKET.

1,173,419.

Specification of Letters Patent.

Patented Feb. 29, 1916.

Application filed August 11, 1915. Serial No. 44,851.

To all whom it may concern:

Be it known that I, GEORGE G. FLOYD, a citizen of the United States, and resident of Chicago, in the county of Cook and State 5 of Illinois, have invented certain new and useful Improvements in Coupling-Pockets, of which the following is a specification.

My invention relates to railway cars and more particularly to a coupler pocket for 10 use in attaching couplers to the end sills of locomotive tenders and cars of like nature.

One of the objects of my invention is to provide an improved form of pocket having a separable supporting shelf capable of 15 reversal.

A further object is to provide means whereby the shelf is retained in position in the pocket without the use of bolts.

A still further object being to provide a 20 shelf adapted to be held in position in the pocket by the pin which holds the coupler shank in position therein.

My invention will be more readily understood by reference to the accompanying 25 drawings, wherein—

Figure 1 is a plan view of the coupler pocket and shelf constructed in accordance with my invention; Fig. 2 is a sectional view on the line 2—2 of Fig. 1 showing in addition, by dotted lines, the relation of the 30 coupler shank and pin; Fig. 3 is a horizontal sectional view on the line 3—3 of Fig. 2, and Fig. 4 is an end view of the shelf.

Referring more particularly to the drawings, it will be observed that the pocket has 35 a web or plate 10 whereby the pocket is fastened to the end sill or other portion of the car. Extending from one side of plate 10 is a pocket having laterally diverging side 40 walls 11, top and bottom walls 12 and 13 respectively having apertures 14 and 15 therein. In the inner end of the pocket and extending into the web 10 are arcuate recesses 16 and 17 at the top and bottom of 45 the pocket, as shown best in Figs. 2 and 3. The parts as described above are in an integral casting.

The shelf by means of which the coupler 50 is supported consists of a flat portion 18 and a vertically offset portion 19, the planes of portions 18 and 19 being parallel. This formation provides a shoulder 20. When the shelf is inserted in the coupler pocket the shoulder 20 abuts against the bottom 55 wall 13 of the pocket. The inner end of

flat portion 18 is adapted to extend into the recess 17 whereby vertical movement of the shelf is prevented. Extending upwardly from portions 18 and 19 are sides 21 and 22 which serve as guides for the coupler shank 60 and also as strengthening webs for the shelf. An aperture 23 is provided in flat portion 18 and adapted to register with apertures 14 and 15 in the pocket. Extending across and underneath the front of the offset 19 is a 65 rib 24 which serves also as a strengthener.

In Fig. 2 the dotted lines show the rear end of a coupler shank as inserted in the coupler pocket and supported on offset 19. The tendency of the coupler is to bear 70 against offset 19, thereby raising the inner end of the shelf. By providing the recess 17 I avoid the tilting of the shelf. Also shown by dotted lines is a pin extending through the apertures 14, 23 and 15, and 75 through the coupler shank, thus holding the several members in position. The pin may be retained by means of a key, as shown by dotted lines. The construction of the pocket is duplicated at its upper portion so that it 80 may be reversed on the end sill. The shelf may be inserted with facility in either position.

As shown, the load is carried on the shelf without the need of bolts or like fasteners, 85 the shelf being retained in vertical position by interlocking engagement with the pocket casting.

I claim:

1. In a device of the class described, the 90 combination of a coupler pocket, a supporting member projecting forwardly from and acting as an extension of said pocket and adapted for interlocking engagement therewith, and a pin adapted to be passed 95 through said pocket, a coupler shank and said supporting member, whereby the supporting member is held against displacement, substantially as described.

2. In a device of the class described, the 100 combination of a coupler pocket formed as a casting and having a recess at the rear of the coupler-shank-receiving cavity, a shelf, the inner end of which is adapted to be accommodated within said recess, and a pin 105 passing through said pocket and said shelf, substantially as described.

3. In a device of the class described, the combination of a coupler pocket, a coupler 110 supporting shelf fitted into and interlocking

with said pocket, and a coupler pivot pin engaging said shelf and preventing removal thereof through the mouth of the pocket, substantially as described.

5. 4. In a device of the class described, the combination of a coupler pocket having recesses, a shelf having a flat bearing portion and provided with side walls and adapted to be inserted in said pocket and to engage 10 one of said recesses, substantially as described.

5. In a device of the class described, the combination of a coupler pocket and a shelf

member, said shelf having a flat bearing portion, and laterally diverging side-walls 15 or ribs, and a shoulder adapted to bear against said pocket, said pocket being provided with means whereby said shelf is held against vertical movement, substantially as described.

Signed at Chicago, Illinois, this 5th day of Aug., 1915.

GEORGE G. FLOYD.
